ATTORNEY.

UNITED STATES PATENT OFFICE.

WILLIAM F. LE SEUR, OF NEW YORK, N. Y.

TRUSS.

SPECIFICATION forming part of Letters Patent No. 606,465, dated June 28, 1898.

Application filed February 9, 1898. Serial No. 669,624. (No model.)

To all whom it may concern:

Be it known that I, WILLIAM F. LE SEUR, a citizen of the United States, residing in New York city, in the borough of Brooklyn, in the State of New York, have invented a certain new and useful Improvement in Trusses for Hernia, of which the following is a specification.

I employ two inwardly-curved springs side by side at a little distance apart and flexibly connected. The pad is carried on a pivot located in the joint between, and the whole is supported on a flexible strap of corresponding breadth, with provisions for adjusting its tightness independently near the upper and lower edges.

The accompanying drawings form a part of this specification and represent what I consider the best means of carrying out the invention.

Figure 1 is a general perspective view. The remaining figures show details on a larger scale. Fig. 2 is an interior view of the pad and the adjacent parts. A portion of the double pocket is broken away to show the spring. Fig. 3 is a top view of the same when in an unstrained condition. Fig. 4 is a corresponding view when the truss is subject to strain on the person. Fig. 5 is a section on the line 5-5 in Fig. 3. Fig. 6 is a corresponding section showing the double pockets and springs in a partially-folded condition assumed when the wearer is in a stooping position. Fig. 7 is a cross-section through the center of the pad and the adjacent parts in a corresponding folded condition. Fig. 8 is an exterior view of a portion.

Similar letters of reference indicate corresponding parts in all the figures where they appear.

A is the pad, which may be of any required size and material.

B and C are springs made from flat steel, the general curvature being reversed near each end. They are spring-tempered and may be surfaced by varnish or otherwise, so as to resist oxidation.

D' D² is a double pocket of fine leather, and E lines of stitching by which they are held in shape and united to a flexible strap or belt G, of woven webbing or other suitable material, of corresponding width. The springs may be

inserted after the stitching is completed by thrusting them through slits d' d² cut in the leather near one end.

55

H is a just sufficiently large washer of metal, and I an adjustable screw inserted through the whole and engaging firmly in the center of the flat side of the pad A.

J is a piece of leather with two straps J' J² 60 of different lengths extending parallel, as shown, and carrying buckles K' K².

M is a piece of leather sewed on the belt G near the opposite end and having two extensions M' M² near the upper and lower edges 65 of the webbing, respectively, perforated to engage with the said buckles.

In the use of the truss the pad is inclined as the location of the rupture shall require, and is firmly set by tightening the screw I. 70 Then the truss is put in place and the straps M' M² are engaged with the buckles K' K² and tightened independently until the right condition is attained. In all ordinary cases no further care will be required, and the pad will 75 remain absolutely immovable, the springs yielding without moving the pad.

The tightness with which the truss should be buckled is insufficient to completely straighten the springs B C under ordinary 80 conditions; but in the strains to which the parts are subjected in vigorous exertions of the wearer these springs may become each straight or curved slightly in the opposite direction. A quality of great importance is due 85 to the dual feature of the springs and straps. When the person of the wearer is much doubled, the springs B C correspondingly double upon each other, the flexible character of the double pocket D' D² readily allowing this 90 and accommodating the truss to every movement of the wearer. The whole or any required portion of the webbing or other flexible material in the belt G easily folds to correspond. The two straps J' J² and M' M², with 95 their buckles, can assume a corresponding partially-folded condition vertically. The inequality in the lengths of the straps J' J² holds the buckles K' K² out of coincidence, so that when this part of the truss is folded they lie 100 out of contact.

Modifications may be made without departing from the principle or sacrificing the advantages of the invention. The curvature of

the springs B C and their length and breadth may be increased or diminished to some extent. I prefer the whole as shown.

I claim as my invention—

- 5 1. In a truss for hernia, the combination of the upper and lower leaf-springs B, C, inwardly curved in a horizontal plane, flexible connections D', D² of leather, pad A secured independently of the springs B, C, a webbing or belt G, and suitable securing means for the latter, as herein specified.
- 10 2. In a truss for hernia, the combination of the inwardly-curved springs B, C, having their ends secured as shown, with the double

pocket D', D², and fastening provision I between them engaging the pad A and washer H, the flexible webbing or belt G, two straps J', J², of differing lengths, two buckles K', K², out of coincidence with two straps M', M², all arranged to serve substantially as herein specified. 15

In testimony that I claim the invention above set forth I affix my signature in presence of two witnesses.

WILLIAM F. LE SEUR.
